UNITED STATES PATENT OFFICE.

JOHN A. BURGER, OF DETROIT, MICHIGAN.

FRICITION-BOARD FOR DROP-FORGING HAMMERS.

No. 901,779.

Specification of Letters Patent.

Patented Oct. 20, 1908.

Application filed August 14, 1907. Serial No. 388,440.

To all whom it may concern:

Be it known that I, JOHN A. BURGER, a citizen of the United States, residing at Detroit, in the county of Wayne and State of Michigan, have invented certain new and useful Improvements in Friction-Boards for Drop-Forging Hammers, of which the following is a specification.

As commonly constructed, the upper die 10 and head of a drop-forging hammer is lifted by means of a wooden strip or board secured at one end to the head and passed between friction rolls which engage it with sufficient force to prevent its slipping when the rolls 15 are turned to feed the board through and lift the great weight of the head. This heavy intermittent crushing action of the rolls often splits the board, making it dangerous to use, and soon by compressing the 20 fibers, causes the board to lose its elasticity and consequent frictional quality which is essential to prevent slipping and premature dropping of the head when raised.

This invention relates to an improved friction board for this purpose, and its object is to provide a board which is less liable to split, crack or break, has greater elasticity and strength, and will last much longer in use than the ordinary wooden strip or board 30 commonly used.

It is also an object of the invention to so construct the board that, should it split, the pieces would still be held in place and injury to the operator therefrom would be prevented.

To this end the invention consists in forming a board of two or more thin strips which are secured together with a strengthening strip of suitable material between, all as hereinafter more fully described, reference being had to the accompanying drawing, in which,

Figure 1 is a diagrammatic front elevation of a drop-forging hammer, with a friction board embodying the invention, in place 45 therein; Fig. 2 is a side elevation of the same with parts broken away to show the friction rolls and board; Fig. 3 is a perspective detail of a portion of a board embodying the invention; and Fig. 4 is a similar view showing a modified construction.

As shown in the drawings, 1 is the machine bed having a seat for the lower die 2, and 3

is a suitable upright frame having guides for the weighted head 4 which carries the upper die 5. To this head one or more friction boards 6 are secured at their lower ends, these boards extending upward between suitable friction rolls 7 which are driven in any suitable manner, as by pulleys 8 on one roll shaft from which motion is transmitted to the other by gears 9. Any suitable mechanism, as indicated at 10 may also be provided to cause the rolls to frictionally engage the board in raising the head and release the same when the head has been raised to a predetermined height to permit it to fall freely. One board 6 may be used in place of the two shown, but I prefer to use two as the narrower boards are less expensive to manufacture, owing to the width of stock:

As shown in Fig. 3, I prefer to construct the boards 6 of two thin strips or boards 11, the grain of which extends longitudinally of the boards, and secure them together with a layer or strip of leather belting 12 or other suitable material between, by gluing. By placing the board under pressure while the glue is setting, the strips will be so firmly united to the leather that they can not be torn apart, and should the strips become split or otherwise broken in use, their parts will still be firmly held to the leather and thus prevented from injuring the operator. The leather not only gives great tensile strength to the board, greatly lengthening its life, but also increases its elasticity and consequent frictional quality.

Material other than leather may be used, as illustrated in Fig. 4, in which a strip of wire netting 13 is glued between the wooden strips, and it is evident that other materials may be used or a strip or layer of wood may be substituted for the leather in certain cases. Other means than gluing may be employed to unite the strips and I therefore do not wish to limit myself to the particular kind of material used or the particular means employed for uniting the strips.

Having thus fully described my invention, what I claim is:

1. A friction board for drop-forging hammers consisting of outer strips of wood forming the friction surfaces of the board, and a strengthening strip of strong flexible ma-

aterial interposed between said outer strips and secured thereto throughout its length.

2. A friction board for drop-forging hammers consisting of strips of material forming the friction surfaces of the board, and a strip of leather interposed between said strips and secured thereto.

In testimony whereof I have signed this specification in presence of two witnesses.

JOHN A. BURGER.
